[57] CLAIM

The ornamental design for a table for massaging and chiropractic therapy, substantially as shown.

DESCRIPTION

FIG. 1 is a front, top and left side perspective view of a table for massaging and chiropractic therapy showing our new design;

FIG. 2 is a rear, top and right side perspective view thereof;

FIG. 3 is a front elevational view thereof;

FIG. 4 is a top plan view thereof;

FIG. 5 is a left side elevational view thereof;

FIG. 6 is a right side elevational view thereof;

FIG. 7 is a rear elevational view thereof;

FIG. 8 is a bottom plan view thereof;

FIG. 9 is a front, top and left side perspective view of a first modified embodiment of the apparatus shown in FIG. 1; and

FIG. 10 is a rear, top and right side perspective view thereof.

FIG. 1

FIG. 2

FIG. 3

FIG. 4

FIG. 5

FIG. 6

FIG. 7

FIG. 8

FIG. 9

FIG. 10
